UNITED STATES PATENT OFFICE.

JOHN L. ALEXANDER AND WILLIAM E. ALEXANDER, OF LEBANON, IND.

SHINGLE-SHAVING MACHINE.

SPECIFICATION forming part of Letters Patent No. 234,217, dated November 9, 1880.

Application filed July 3, 1880. (Model.)

To all whom it may concern:

Be it known that we, JOHN L. ALEXANDER and WILLIAM E. ALEXANDER, citizens of the United States, residing at the city of Lebanon, in the county of Boone and State of Indiana, have invented a new and useful Shingle-Shaving Machine, of which the following is a specification.

This invention relates to an improved machine for dressing shingles, and has for its object to provide an apparatus by means of which a shingle may be shaved on both sides simultaneously to the desired bevel or taper from the butt to the front edge, as more fully hereinafter specified. These objects we attain by the mechanism illustrated in the accompanying drawings, in which—

Figure 1 represents a side elevation of our improved apparatus; Fig. 2, a horizontal sectional view; Fig. 3, a top view of the frame carrying the working parts of our invention; Fig. 4, a view of one of the cutter-carriers and sliding blocks detached, with a portion of the frame broken away, showing one of the bearings in which is journaled the rollers; and Fig. 5 represents a vertical sectional view of the knife-carrying frames, showing the operation of the shingle-support.

The letter A indicates the frame of the machine, which may be constructed of wood or any other suitable material, and which is mounted on legs B at each end. At or near one end of the frame is mounted the driving-gear of the machine, consisting of the driving-shaft D and fly-wheel E, with pinion F intermeshing with cog-wheel G, mounted on the shaft H, journaled in bearings I upon the frame. The fly-wheel E provides for a steady movement when the cutters meet with knots and the like.

The letter K indicates a frame secured rigidly to the forward end of the frame A. The said frame is constructed of two rectangular side sections, h, which are clamped together against intervening blocks L by means of through-bolts M and N in such manner that the forward ends of the sections will gradually approach each other for the purpose of gradually bringing the cutting-knives together as they are moved forward, as more fully here-

inafter specified. The front ends of the sections are slotted longitudinally at O for the passage of the through-bolts M, so that the distance between the ends of the sections may be varied to vary the bevel of the shingle. The upper and lower bars of the sections h are provided with ways P, upon which are adapted to slide the cutter-carriers, the said carriers consisting each of a frame, Q, secured to a sliding block, R, the said frame Q being formed at its end 60 with lugs S, which embrace the ways P on the sections h.

The letter T indicates the knives, which are secured to heads U attached to the sliding frames, and the said heads are secured each 65 to one end of the bifurcated pitman V, which is connected to the crank-pin X on the gear-wheel. The heads U have inclined faces, which throw out the shavings as the cutters shave the shingle.

To the upper and lower edges, near the ends of the sliding blocks R, are secured the spring-bars Y, to the free ends of which are attached the slides A', adapted to move in transverse ways B' in the frame Q. The free ends of 75 said slides are provided with bearings for the journals of the upright rollers C', which are adapted to bear against opposite sides of the shingle to be dressed, and by means of the yielding pressure imparted to them by the 80 spring-bars to adjust themselves to the bevel of the shingle, so as to firmly clasp and hold the same.

The letter D' indicates a stop interposed between the two blocks between the front sections of the frame K, the said stop being provided with a grooved bearing at its edge, against which the shingle rests while being shaved or dressed.

The letter E' indicates a grooved support, 90 which is pivoted to a hinged frame, F', directly under the frame K. The said support is provided with an arm, G', from which extends a cord, H', passing over a pulley, I', and provided with a weight, K'.

The bottom edge of the shingle rests in the groove of the support E', which is held in position up against the bottom edges of the sliding blocks R by the weighted cord attached to the arm G', and as the knives approach the 100

shingle the heads U strike the incline of the open frame F', which is hinged to the support E' at a point near the arm G', and forces the end of the support, which is made in the form of a chute, downward in a tilting position, as shown by dotted lines in Fig. 5, the free end being held up against the sliding blocks by means of the weighted cord and arm, so that on the return of the knives, which also carry with them the shingle, the shingle is released, and the end dropping into the chute end of the support, it slides through the open frame F' and drops to the ground, and the constant gravitational force of the weight K' acting upon the cord serves to throw the support back into position for another operation.

The through-bolts M are provided with rubber springs L', by means of which the frame-sections are permitted to yield when the knives meet with any unusual obstructions in the shingles, in order to prevent injury.

The operation of our invention is follows: The shingles to be dressed are dropped into the opening at the top of the frame K, the forward edge of the shingle resting in the groove in the edge of the stop and the lower edge in the grooved support, which is held in normal position by means of the cord and weight. The sliding knife-carriers being put in operation by the gearing, the knives shave the shingles from the butt to the front edge on the forward stroke, being caused to approach each other to cut the desired bevel by means of the ways on the frame K. Upon the return-stroke the shingle is drawn back by the knives, forcing the support downward until it is cleared, when the finished shingle will drop out of the machine at the bottom.

Having thus described our invention, what

we claim, and desire to secure by Letters Patent, is—

1. In a machine for dressing shingles, the frame having converging sections provided with ways, the grooved stop, and the independent or duplicate sliding frames provided with knife-carriers adapted to travel on the ways, whereby the knives are caused to approach each other on their forward movement, in combination with the rollers mounted between the knife-carrying frames and journaled in transverse slides, and the spring-bars for the purpose of operating said rollers, substantially as specified.

2. In combination with the knife-carrying frames and mechanism for operating the same, the support hinged to the open frame, said frame being pivoted between the knife-carrying frames and the gravitational weight, the whole arranged to operate substantially as specified.

3. The cutter-heads having inclined faces, as shown, to throw out the shavings, and cutters or knives, combined with the reciprocating frames, the bearing-rollers, the spring bars, and grooved stop D, as and for the purposes specified.

4. In a shingle-machine, the combination of the adjustable frames having ways or guides, the grooved stop for holding the shingle to the knives, the reciprocating knife-carriers, the rollers, the knife-blades, the pivoted support, the bifurcated frame, and the weight, all constructed and arranged to operate substantially as specified.

JOHN L. ALEXANDER.

WILLIAM E. ALEXANDER.
